CAN COOLING AND TRANSFERRING MECH-
ANISM

Frank D. Chapman, Berlin, Wis.

Application November 27, 1931
Serial No. 577,533

19 Claims. (Cl. 257—23)

The present invention relates in general to improvements in the art of heat transfer, and relates more specifically to improvements in the construction and operation of apparatus for cooling heated objects such as food laden cans.

An object of the invention is to provide improved cooling apparatus for rapidly and effectively reducing the temperature of successive objects such as food laden cans, upon delivery thereof from a heater.

It is customary in the canning industry to heat treat or process various commodities after the same have been packed in sealed containers such as cylindrical tin cans. Such heat treatment is frequently effected by passing the food laden sealed cans in succession through a continuous cooker or sterilizer. When the treated cans are delivered from the processing apparatus they are in highly heated condition, and it is desirable to thereafter reduce the temperature by dispersing the internal heat of each confined batch, as rapidly and effectively as possible.

It is a more specific object of the present invention to provide a cooler which will effectively and automatically reduce the temperature of successive food laden cans as rapidly as they are delivered from the heat treating apparatus.

Another specific object of the invention is to provide a cooling device of large capacity, where in the successive objects are initially cooled during delivery thereof to a final cooler, so as to effect a relatively great range of temperature reduction.

Still another specific object of the invention is to provide improved cooling apparatus especially adapted for the treatment of any commodity, whether solid or liquid, packed in cylindrical containers such as tin cans.

An additional object of the invention is to provide a heat transfer device which may be conveniently manipulated to produce various desirable conditions of operation.

These and other objects and advantages of the invention will be apparent from the following detailed description.

The improved can transporting mechanism for transferring the successive food-laden cylindrical cans to and from the rotor of the main cooler, and which is shown diagrammatically in the drawing, forms the subject of a divisional application Serial No. 672,543, filed May 24, 1933.

A clear conception of embodiments of the several features constituting the present invention, and of the mode of constructing and of operating coolers and can transferring mechanism built in

accordance therewith, may be had by referring to the drawing accompanying and forming a part of this specification in which like reference characters designate the same or similar parts in the several views:

Fig. 1 is a side elevation of one of the improved cooling units, showing the initial and final coolers and the mechanism for discharging the cans from the final cooler;

Fig. 2 is a part sectional end elevation of the improved cooler, looking toward the can inlet end and the initial cooler; and

Fig. 3 is a part sectional end view of the improved cooler looking toward the can discharge end of the unit.

While the invention has been shown and described herein as being specifically applied to coolers for cylindrical tin cans containing food products or comestible substances, it is to be understood that some of the features are more generally applicable to the treatment and transportation of other objects, and also to the treatment of containers packed with substances other than those referred to.

The improved cooling apparatus specifically illustrated in Figs. 1, 2 and 3, comprises in general an initial conduit cooler 6 and a final drum cooler 5, through which the cans are transported in succession. This apparatus is especially adapted for the treatment of highly heated food laden cans or the like, which are cylindrical in shape.

The initial cooler 6 consists of a zig-zag or corrugated conduit 7 surrounded by an endless chain conveyor 8 which is adapted to deliver the successive highly heated food laden cans from a supply chute 9 to the upper end of the conduit 7. The interior of the cooling conduit 7 is provided with a can transporting chain conveyor 10 for gradually propelling the cans in succession downwardly through the zig-zag portion of the conduit 7, and the lower end of this portion of the cooler conduit communicates directly with the upper part of the inlet end of the final cooler 5, through a conduit 11 and a can inlet opening 100.

12. The conduit 11 is not sufficient in size to permit the cans to pass therethrough, but merely serves to permit unrestricted flow of cooling liquid from the final cooler 5 into the lower end of the conduit 7. The upper part of the zig-zag portion of the conduit 7 is provided with an overflow 13 through which the upwardly flowing cooling liquid is finally delivered in regulated quantities.

110 The final cooler 5 is of the drum type and con-

sists of an outer cylindrical fixed casing 14 having stationary helical can guides 15 secured to the interior peripheral wall thereof, and a rotor 16 rotatably supported within the casing 14 and having a series of peripheral radial flights 17 adapted to urge the successive cans spirally along the helical guides 15. The delivery end of the stationary casing 14 is provided with an inwardly projecting cup-shaped head 18 which 10 forms an annular can discharge and cooling medium inlet space 19.

A can discharge conduit 20 having an endless chain can conveyor 21 operable therethrough, communicates with the lower part of the annular space 19 of the final cooler 5 and rises therefrom to the level of the overflow 13 associated with the initial cooler conduit 7, and an auxiliary cooling liquid inlet 22 may be provided at the upper end of this discharge conduit 20. The annular space 19 besides communicating with the can delivery conduit 20, is also provided with a cooling liquid inlet 23 for admitting the major portion of the cooling medium directly to the interior of the casing 14 at the can delivery end thereof. The rotor 16 and the several endless chain can conveyors associated with the cooling apparatus, are simultaneously operable by means of the gearing 24, and the finally cooled cans 28 are discharged by gravity from the final conveyor 25 upon a delivery chute 26.

During normal operation of the improved cooler, the chain conveyors 8, 10, 21 and the rotor 16 are being operated continuously by means of the gearing 24, and the successive food laden heated cans 28 are being delivered from the can supply chute 9 to the upper end of the initial cooler 6, by the chain conveyor 8. Cooling liquid at predetermined temperature is being admitted to the can delivery end of the final cooler 5 through the inlet 23, and flows longitudinally through the casing 14 in a direction opposite to the direction of travel of the cans 28. Upon reaching the can inlet opening 12 and the conduit 11, the cooling liquid flows into and upwardly through the zig-zag conduit 7 and is eventually discharged through the outlet 13. In order to maintain the liquid within the can discharge conduit 20 at sufficiently low temperature, cooling liquid at or below the temperature of that admitted to the main inlet 23, may be admitted to the upper end of the conduit 20 through the auxiliary inlet 22.

The heated cans 28 passing downwardly through the zig-zag conduit 7 have their temperature initially reduced by the cooling liquid rising through this conduit, to such an extent that they may be effectively finally cooled in a main cooler 5 of relatively small size. The temperature range of the cooling liquid at the can outlet and inlet ends of the conduit 7, may for example be from ninety degrees to one hundred and twenty degrees Fahrenheit. While passing through the main cooler casing 14 which is filled with cooling liquid surrounding the rotor 16, the temperature of the cans 28 is further reduced so that when the food laden cans enter the delivery conduit 20, they are cooled to substantially the desired extent. The temperature range of the cooling liquid at the can outlet and inlet ends of the casing 14, may for example, be from sixty degrees to ninety degrees Fahrenheit, and such temperature range may be readily maintained in a relatively small and compact main cooler 5 of large capacity, by virtue of the effective initial cooling accomplished by the initial conduit cooler

6. The combination of initial and final coolers 6, 5, therefore, permits more effective and rapid cooling of the cans 28 than would be possible with either a conduit or a drum type of cooler when used alone, since the temperature of the cans 28 is rapidly initially reduced and is more slowly finally reduced in the successive types of coolers operating in conjunction with each other at maximum efficiency.

From the foregoing description it will be apparent that the present invention provides a simple, compact and highly efficient cooler for food laden cylindrical cans or the like. The cooler functions to quickly initially reduce the temperature of the successive cans 28, and to effectively finally cool the same after the initial reduction in temperature has been effected. The can transferring mechanism functions to automatically transfer the cans from the initial cooler to the final cooler and from the final cooler to the discharge conveyor, and this portion of the system is obviously not confined to a cooler but may be more generally applied to other machines wherein cans are to be transferred from one type of a conveyor to another. All portions of the mechanisms are moreover conveniently accessible for inspection, and the temperatures of the cooling liquids admitted through the inlets 22, 23 may be readily regulated to meet various conditions of operation.

It should be understood that it is not desired to limit the invention to the exact details of construction and operation herein shown and described, for various modifications within the scope of the claims may occur to persons skilled in the art.

It is claimed and desired to secure by Letters Patent:

1. A cooling unit comprising, an initial conduit type cooler, a second drum type cooler, means for directly transferring objects in succession from said initial to said second cooler, and conduit means connecting said coolers independently of said transferring means.

2. A cooling unit comprising, an initial conduit type cooler, a second drum type cooler, means for directly transferring objects in succession from said initial to said second cooler, and means independent of said object transferring means for conducting cooling liquid from one of said coolers into the other cooler.

3. A cooling unit comprising, an initial conduit type cooler, a second drum type cooler, means for directly transferring objects in succession from said initial to said second cooler, and means for passing cooling liquid through said coolers in succession in a direction opposite to the direction of travel of the objects therethrough.

4. A cooling unit comprising, an initial cooler consisting of a zig-zag conduit and means for transporting objects longitudinally therethrough, a second cooler consisting of a casing and means for transporting objects spirally therethrough, and means for directly transferring objects in succession from the transporting means of said initial cooler to the transporting means of said second cooler.

5. A cooling unit comprising, an initial cooler consisting of a zig-zag conduit and means for transporting objects longitudinally therethrough, a second cooler consisting of a casing and means for transporting objects spirally therethrough, means for directly transferring objects in succession from the transporting means of said initial cooler to the transporting means of said

- second cooler, and means for passing cooling liquid through said coolers in succession. 80
6. A cooling unit comprising an initial cooler consisting of a zig-zag conduit and means for transporting objects longitudinally therethrough, a second cooler consisting of a casing and means for transporting objects spirally therethrough, means for directly transferring objects in succession from the transporting means of said initial cooler to the transporting means of said second cooler, and means for passing cooling liquid through said coolers in succession in a direction opposite to the direction of travel of the objects therethrough. 85
15. 7. A cooling unit comprising, an initial cooler, a second cooler, means for transferring objects in succession from said initial to said second cooler, and means independent of said object transferring means for conducting cooling liquid from said second to said initial cooler. 90
20. 8. In combination, a conduit cooler having a can inlet and a cooling liquid outlet at the same end thereof, a drum cooler having a can inlet communicating directly with the opposite end of said conduit cooler, and means for conducting liquid directly from said drum cooler to an intermediate portion of said conduit cooler. 95
25. 9. In combination, a circular elongated casing having a can transporting rotor therein adapted to urge successive cans around and along the casing interior, means for admitting cans to one end of said casing, means for admitting liquid to the opposite end of said casing, a conduit communicating with the can inlet end of said casing at said can admission means, and means for delivering liquid from said casing to said conduit in advance of said can admission means. 100
30. 10. A cooling unit comprising, a pair of laterally spaced upwardly extending conduits at least one of which defines a zig-zag path, and an intermediate drum communicating with the lower end portions of both of said conduits. 105
35. 11. A cooling unit comprising, a pair of laterally spaced upwardly extending conduits at least one of which defines a zig-zag path, and an elongated cylindrical drum communicating at its opposite ends with the lower end portions of said conduits. 110
40. 12. A cooling unit comprising, a pair of laterally spaced upwardly extending conduits at least one of which defines a zig-zag can path, an intermediate drum communicating with the lower end portions of both of said conduits, and means for transporting cans in succession through said conduits and said drum. 115
45. 13. A cooling unit comprising, a pair of laterally spaced upwardly extending conduits at least one of which defines a zig-zag can path, an elongated cylindrical drum communicating at its opposite ends with the lower end portions of said conduits, and means for transporting cans in succession through said conduits and said drum. 120
50. 14. A cooling unit comprising, a pair of laterally spaced upwardly extending conduits, an intermediate drum communicating with the lower portions of both of said conduits, and means for constantly advancing cylindrical cans in succession through said conduits and said drum. 125
55. 15. A cooling unit comprising, a drum, laterally spaced elongated inlet and discharge conduits extending upwardly from the opposite ends of said drum, mechanism for urging cans in succession through said inlet conduit and said drum and said discharge conduit, and means for circulating liquid through said inlet conduit and said drum in a direction opposite to the travel of the cans. 130
60. 16. A cooling unit comprising, a drum, an elongated zig-zag can inlet conduit extending upwardly from one portion of said drum, an elongated can discharge conduit extending upwardly from another portion of said drum, means for transporting cans in succession through said inlet conduit and said drum and said discharge conduit, and means for progressively cooling the advancing cans. 135
65. 17. A cooling unit comprising, a drum having means for transporting cans spirally therethrough, an elongated zig-zag conduit extending upwardly from one portion of said drum, an elongated conduit extending upwardly from another portion of said drum, and means for advancing the cans through said conduits. 140
70. 18. A cooling unit comprising, a drum having means for transporting cans spirally therethrough, an elongated can inlet conduit extending upwardly from one end of said drum and having means for transporting cans longitudinally therethrough, and an elongated can discharge conduit extending upwardly from the opposite end of said drum and having means for transporting the cans longitudinally therethrough. 145
75. 19. A cooling unit comprising, a drum having means for transporting cans spirally therethrough, an elongated can inlet conduit extending upwardly from one end of said drum and having means for transporting cans longitudinally therethrough, an elongated can discharge conduit extending upwardly from the opposite end of said drum and having means for transporting the cans longitudinally therethrough, and means for circulating cooling liquid through said drum and said inlet conduit in a direction opposite to the can travel. 150
